Fig. 1.

Fig. 2.

Fig. 3.

Fig. 4.

FIG. 1 is a side perspective view of a corrosion meter showing our new design;

FIG. 2 is a side elevational view thereof, all sides being substantially the same as the side shown in this view;

FIG. 3 is a top plan view thereof; and

FIG. 4 is a bottom plan view thereof.

The dominant features of the design are embraced in the portions shown in solid lines. The broken line showing of the plug in FIG. 2 has been omitted from the other views for convenience of illustration.

We claim:

The ornamental design for a corrosion meter, as shown and described.
